UNITED STATES PATENT OFFICE.

JOHN C. KOCH, OF BERLIN, GERMANY.

DESIGN FOR A BOOK OR ALBUM.

SPECIFICATION forming part of Design No. 19,525, dated December 24, 1889.

Application filed October 14, 1889. Serial No. 327,016. Term of patent 7 years.

To all whom it may concern:

Be it known that I, JOHN CASPAR KOCH, a citizen of the United States, residing in Berlin, Prussia, Germany, have invented and produced a new and original Design for Books or Albums, of which the following is a specification, reference being had to the accompanying drawings, forming part hereof, in which—

Figure 1 represents two leaves as in an open album, and Fig. 2 is a sectional view.

The leading feature of this design consists of a book or album, the outline or configuration of the leaves of which is triangular.

The lines *a b*, bounding the top and bottom edges of the leaf, are at an acute angle to each other. The third side *c* is the line of attach-

ment at the back. The point *d* is usually more or less rounding.

The design of the openings *e f* in the album-leaves for the pictures may vary without changing the leading feature of my design, and in some kinds of album and book leaves there are no openings.

What I claim is—

In a design for a book, the design of the leaves, substantially as herein shown and described.

Signed by me this 8th day of October, 1889.

JOHN C. KOCH.
